UNITED STATES PATENT OFFICE.

MAHLON S. CONLY, OF INDIANAPOLIS, INDIANA, ASSIGNOR OF TWO-THIRDS
TO THOMAS H. BUTLER AND ORANGE R. WEAVER, BOTH OF SAME PLACE.

RETORT FOR AMMONIA ICE-MAKING APPARATUS.

SPECIFICATION forming part of Letters Patent No. 298,669, dated May 13, 1884.

Application filed August 10, 1883. (No model.)

To all whom it may concern:

Be it known that I, MAHLON S. CONLY, of the city of Indianapolis, county of Marion, and State of Indiana, have invented certain new and useful Improvements in Retorts for Ammonia Ice-Making Apparatus, of which the following is a specification.

The general process of forming ice by the use of ammonia, and which consists, essentially, in producing in a "retort" ammonia-gas from liquid ammonia, or ammonia and water, passing the same through a cooler and thereby condensing it, then passing it through a series of large pipes in the "refrigerator," where it expands and absorbs heat, and finally passing it into an "absorber," where it is taken up by water and put in condition to be again passed into the retort and through the same process, is no part of my present invention, and will not be further described herein.

My present invention relates to the construction and method of using that portion of the apparatus known as the "retort;" and it consists in an arrangement of tubes and partitions whereby the aqua-ammonia is subjected to a constantly-increasing heat from hot water, which passes through tubes in said retort and around the outside of it, the aqua-ammonia at the same time passing in the opposite direction through the retort around the partitions therein, as will be presently more fully described.

Referring to the accompanying drawings, which are made a part hereof, and on which similar letters of reference indicate similar parts, Figure 1 is a side elevation of a complete apparatus for producing ice, of which my improved retort forms a part; Fig. 2, a horizontal sectional view on the dotted line $z-z$; Fig. 3, a longitudinal vertical sectional view, looking to the left from the dotted line $y-y$; and Figs. 4, 5, and 6, transverse vertical sectional views, looking to the right from the dotted lines $x-x$, $w-w$, and $v-v$, respectively.

In said drawings, the portions marked A represent the shell of the retort; B, a casing surrounding the same; C, the hot-water inlet; D, the hot-water outlet; E, the aqua-ammonia-inlet pipe; F, the ammonia-gas outlet; G,

the weak-aqua-ammonia outlet; H, the condenser for the ammonia-gas; I, the liquid-gas reservoir; J, the cooler for the weak aqua-ammonia; K, a pipe leading from the liquid-gas reservoir to the refrigerator; L, said refrigerator; M, a pipe leading from the refrigerator to the absorber; N, a pipe leading from the cooler J to the absorber; O, said absorber; P, a pipe leading from said absorber to a force-pump; Q, said force-pump, which draws the aqua-ammonia from the absorber through pipe P, and forces it to the retort through pipe E; and R, a "circulation-pump" attached to the refrigerator by pipes $R' R^2$, which is for the sole purpose of keeping the salt-water therein in circulation.

As hereinbefore stated, my present invention relates to the retort only, and the other portions will not therefore be further described herein.

The shell A is constructed much as a steam-boiler is constructed, with the pipe-flues a extending from end to end thereof. It has also two partitions, $a' a^2$, one of which extends from one end to near the other end, and the other of which extends from the last-mentioned end back to near the first. Said partitions are so arranged as to divide the tubes a into groups. The casing B surrounds the shell A from the bottom to near the top, leaving a space between the outside of said shell and the inside of said casing. This space is divided into two compartments by a longitudinal partition, b . The spaces between the ends of the shell A and casing B are each divided into two unequal spaces by partitions $b' b^2$, which are practically continuations of the partitions $a' a^2$. Into the smaller of these spaces, at each end, three of the pipes a open, and into the larger of said spaces six of said pipes. Into one of these smaller spaces the hot-water-inlet pipe C enters, and the hot water which flows in through this pipe passes on through the pipes and out into the space b^3 , between the shell A and casing B, on the corresponding side of the partition b . The hot water then flows out into the larger space at the opposite end, and back through the middle group of pipes, to the larger space at the first end. From this space

the water passes through the final group of pipes and the space b^4 to the overflow-pipe D, and passes off. The strong aqua-ammonia is forced through the pipe E into the shell A, 5 at the opposite end of the retort from that at which the hot water enters, and enters the left-hand compartment of said shell, (see especially Fig. 4,) surrounding the group of pipes in said compartment, and flowing to the 10 opposite end of the shell, in contact with said pipes, where it passes around the end of the partition a' , into the middle compartment, and thence back to the end at which it entered, and around the end of the partition a' , into 15 the right-hand compartment, and finally, after passing through said compartment, that portion that has not been generated into gas passes out through the pipe G into the cooler I, having become by this time a weak ammonia-liquor, 20 most of the ammonia having been generated into gas and passed off up the pipe F into the condenser H.

By tracing the course of the hot water and that of the ammonia-liquor, as above described, 25 it will be seen that the entrance and exit of each is at the opposite point in the retort from that of the other—*i. e.*, the ammonia-liquor enters at the point where the water passes out, (and, having had a portion of its heat taken up 30 during its passage through the retort, is the coolest,) and passes out at the point where the water enters. The ammonia-liquor is thus subjected to a constantly-increasing heat in its passage through the retort, and at the point 35 of leaving said retort is subjected to a heat approaching 212° Fahrenheit, the water being preferably raised to that degree of heat before being introduced into the casing surrounding the shell of the retort and the pipes passing 40 through the same.

Having thus fully described my said invention, what I claim as new, and desire to secure by Letters Patent, is—

1. In an ice machine or apparatus, a retort 45 consisting of a shell having tubes or pipes ex-

tending through from end to end, and partitions alternately extending from one end to near the other, in combination with the hot-water, aqua-ammonia, and gas pipes, substantially as set forth. 50

2. In a retort for generating ammonia-gas, a series of pipes and partitions whereby the aqua-ammonia is caused to flow in one direction through the retort, and the hot water is caused to flow in the other direction, thus subjecting the aqua-ammonia to a constantly-increasing heat, substantially as set forth. 55

3. In a retort for generating ammonia-gas, a series of pipes connecting with a hot-water inlet at one end, and arranged to secure several passages of the water through the retort before passing out at the other, and a series of partitions forming compartments connected with an aqua-ammonia inlet at a point near the hot-water outlet, and arranged to secure 60 several passages of the aqua-ammonia through the retort in contact with the hot-water pipes before passing out at a point near the hot-water inlet, thereby subjecting the aqua-ammonia to a constantly-increasing heat and 65 greatly increasing the amount of gas generated by the process, substantially as set forth.

4. The combination of the shell A, having pipes a and partitions a' , the casing B, surrounding the shell A, and having the spaces 75 between itself and said shell divided into compartments by partitions, a hot-water inflow-pipe, C, a hot-water outflow, D, an aqua-ammonia inflow, E, an ammonia-gas outflow, F, and a weak-ammonia-liquor outflow, G, said 80 several parts being arranged and operating substantially as shown and specified.

In witness whereof I have hereunto set my hand and seal, at Indianapolis, Indiana, this 4th day of August, A. D. 1883.

MAHLON S. CONLY. [L. S.]

In presence of—

C. BRADFORD,
E. W. BRADFORD.
